DESIGN FOR A GRILLE OR THE LIKE

George Wyland Fowler, Carbondale, Pa., assignor to Hendrick Manufacturing Company, a corporation of Pennsylvania

Application October 4, 1933. Serial No. 49,400

Term of patent 7 years

To all whom it may concern:

Be it known that I, GEORGE WYLAND FOWLER, a citizen of the United States, residing at Carbondale, in the county of Lackawanna and State of Pennsylvania, have invented a new, original, and ornamental Design for a Grille or the like, of which the following is a specification, reference being had to the accompanying drawing, constituting a part hereof, the same consisting of one figure which is a front elevational view of a grille or the like, showing my new design, said grille being flat and of immaterial thickness.

I claim:

The ornamental design for a grille or the like, substantially as shown and described.

In testimony whereof, I have hereunto subscribed my name this 30th day of September 1933.

G. WYLAND FOWLER.
